(57) **CLAIM**

The ornamental design for a ceiling lampholder to accept a fluorescent lamp, as shown and described.

DESCRIPTION

FIG. 1 is a side, front perspective view of the ceiling lampholder to accept a fluorescent lamp showing our new design; FIG. 2 is a front view thereof;

FIG. 3 is a right side view thereof, the left side view being a mirror image thereof;

FIG. 4 is a rear view thereof; and,

FIG. 5 is a bottom side view thereof, the top side view being a mirror image thereof.

The broken lines showing the bracket-like elements in FIG. 4 and the electrical conductors in FIGS. 1-5 is for illustrative purposes only and forms no part of the claimed design.
